UNITED STATES PATENT OFFICE.

RUDOLF HERRMANN, OF OFFENBACH-ON-THE-MAIN, GERMANY, ASSIGNOR
TO FIRM OF HUPPE & BENDER, OF OFFENBACH-ON-THE-MAIN, GERMANY.

HANDLE FOR TRUNKS, &c.

SPECIFICATION forming part of Letters Patent No. 720,803, dated February 17, 1903.

Application filed December 8, 1902. Serial No. 134,358. (No model.)

To all whom it may concern:

Be it known that I, RUDOLF HERRMANN, a subject of the German Emperor, residing and having my post-office address at 13 Ludwig-
strasse, Offenbach-on-the-Main, Germany,
have invented certain new and useful Im-
provements in Handles for Trunks and the
Like, of which the following is a specification.

My invention relates to improvements in
handles for trunks, portmanteaus, and the
like; and the objects of my improvement are,
first, to so shape two handles that on bringing
them together they form a single handle with
a single axis; second, to hinge the two handles
upon the two detachable parts, respectively, of
a trunk, portmanteau, and the like; third, to
provide two projecting pins in the axis of one
of said handles; fourth, to provide two tubes in
the axis of the other of said handles, the two
tubes being so slotted as to allow the projecting
pins of the other handle to enter and to again
withdraw when said two handles are turned
aside, but to retain same when the two handles
are brought together; fifth, to provide the one
handle with an inward projection, and, sixth,
to provide the other handle with an elastic
latch for engaging the said projection of the
first handle. I attain these objects by the
mechanism illustrated in a mode of execution
in the accompanying drawings, in which—

Figure 1 is an elevation of the two handles
attached to the two bow-frames of a portman-
teau, the handles being shown in their closed
positions and partly in section. Fig. 2 is a
plan of the same, the handles being shown in
their opened positions and partly in section.
Fig. 3 is a vertical cross-section through the
same on the line A B in Fig. 2, the hinge of
the left handle being shown in a section
through the line C D in Fig. 2; and Fig. 4 is
a cross-section through the line E F in Fig. 1.

Similar letters of reference refer to similar
parts throughout the several views.

The two handles *a* and *a'* are shown as at-
tached to a portmanteau by means of four
hinge-plates *b b' b' b*. The two hinge-plates
b b are assumed to be both made in one piece
with a plate *e*, which can be secured on the
one bow-frame *c* by means of rivets *l l* or other-
wise. The two other hinge-plates *b' b'*, how-
ever, are assumed to be made each in one

piece with a plate *e'*, so as to facilitate the
mounting of the parts. The two plates *e'* are
secured on the other bow-frame *c'* by means
of rivets *l' l'* or otherwise.

55

To the two hinge-plates *b b* on the one bow-
frame *c* two pins *d d* are so riveted, with the aid
of the two washers *k k*, as to project outward.
To the two hinge-plates *b' b'* on the other
bow-frame *c'* also two pins *d' d'* are, in a simi-
lar manner, riveted with the aid of the two
washers *k' k'*, but they project inward. The
pins *d d d' d'* serve as axles for the handles
a and *a'*, respectively, which are mounted
to turn on them. The ends of the one han-
dle *a* are so formed as to bear against the
hinge-plates *b b*, and, besides this, they are
so cut out (see Figs. 1 to 3) as to allow of the
ends of the other handle *a'* engaging in the
cuts when the portmanteau is closed—*i. e.*, 70
when the bow-frame *c* engages in the bow-
frame *c'*. (Vide Fig. 3.) The ends of the
other handle *a'* are similarly shaped; but
they are, moreover, provided with tubes *ff*
surrounding and projecting beyond the pins 75
d d'. The tubes *ff* are provided with slots
g g, into which the pins *d d* of the opposed
handle *a* can engage. The slots *g g* are so
placed as to allow the pins *d d* to enter or to
withdraw only when the two handles are 80
turned downward, as is clearly shown at Figs.
2 and 3. When the portmanteau is closed—
i. e., when the two bow-frames *c* and *c'* en-
gage in each other and the two pins *d d* of
the one handle *a* have entered the cavities of 85
the tubes *ff* through the slots *g g*—all that is
required for securing the portmanteau in its
closed position is merely to turn upward the
two handles *a* and *a'*. (See Fig. 1.) Then the
two tubes *ff* will have so changed their posi- 90
tions as to retain the pins *d d* and prevent
them from getting back. For the purpose of
securing the two handles in their closed po-
sitions the one handle *a* is preferably pro-
vided with an elastic latch *h* and the other 95
handle *a'* with an inward projection *i*, Figs.
2 and 4, behind which the hooked arm *h'* of
the latch *h* snaps. On depressing the latch
h the two handles *a* and *a'* can be detached
and turned downward to open the portman- 100
teau.

Of course, where it is so preferred, the elas-

tic latch *h* may further be locked by means of a suitable bolt and key (not shown) in any known manner.

5 The handles described above can be varied without deviating from the spirit of my invention, and they can also be applied to a trunk or the like.

What I claim as my invention, and desire to secure by Letters Patent, is—

10 1. The combination with a handle hinged upon the one part of a trunk, portmanteau and the like, of another handle hinged upon the other detachable part of said trunk, portmanteau and the like, the said two handles forming when brought together a single handle with a single axis, a projecting pin arranged in the axis of one of said handles, a tube arranged in the hinge-axis of the other of said handles and provided with a slot to 20 allow said projecting pin to enter and to again withdraw when said two handles are turned aside, said tube serving for securing said projecting pin when said two handles are brought together, and means for securing 25 said two handles when brought together and for again releasing them, substantially as set forth.

2. The combination with a first handle, of means for hinging said first handle upon the 30 one part of a trunk, portmanteau and the like, a second handle, means for hinging said second handle upon the other detachable part of said trunk, portmanteau and the like, the said two handles forming when brought together a single handle with a single axis, a projecting pin secured on said hinging means on either part of said trunk, portmanteau and the like, in the axis of same, a tube secured on the handle on the other part of said trunk, 35 portmanteau and the like in the axis of same and provided with a slot to allow said projecting pin to enter and to again withdraw when said two handles are turned aside, said tube serving for securing said projecting pin when

45 said two handles are brought together, an inward projection provided on one of said two handles, and an elastic latch provided on the other of said two handles for engaging and releasing said inward projection, substantially as set forth.

50 3. The combination with a first handle, of a first pair of hinge-plates secured on the one part of a trunk, portmanteau and the like, the pins of said first pair of hinge-plates for said first handle being arranged in the same 55 center line and projecting outward, a second handle, a second pair of hinge-plates secured on the other part of a trunk, portmanteau and the like, the pins of said second pair of hinge-plates for said second handle being arranged in the same center line and projecting inward, so that on closing said trunk, portmanteau and the like and bringing together said two handles the latter form a single handle with a single axis, while the projecting 60 ends of said hinge-pins are opposed to each other in the common center line, two tubes secured on one of said handles and surrounding its two hinge-pins, they projecting beyond the latter and being each provided with 65 a slot to allow the respective projecting pin end of the other handle to enter and to again withdraw when said two handles are turned aside, said two tubes serving for securing 70 said projecting pin ends when said two handles are brought together, an inward projection provided on one of said two handles, and an elastic latch provided on the other of said two handles for engaging and releasing said inward projection, substantially as set forth.

75 In testimony whereof I have signed my name to this specification in the presence of two subscribing witnesses.

RUDOLF HERRMANN.
